YARN DELIVERY ARRANGEMENT FOR
CREELS

Frank B. Javery and Raymond C. Longvall,
Worcester, Mass., assignors to Warp Compress-
ing Machine Company, Worcester, Mass., a
corporation of Massachusetts

Application September 1, 1939, Serial No. 293,102

6 Claims. (Cl. 57—106)

The present invention relates to creels or spool stands, and has for its object to provide an improved yarn delivery arrangement, whereby yarn ends leading from a large number of separate packages or spools may be delivered to a twisting or other textile machine, without the individual yarns rubbing against each other, in advance of the twisting or other operation.

According to the invention, the improved delivery arrangement is characterized by the fact that each yarn is withdrawn endwise from its package, and is guided separately through an individual tensioning device, to the point of twisting. As a result, yarn ends from adjacent packages in the creel, do not come into contact with each other until they reach the point of twisting, thereby eliminating any chafing or rubbing between separate yarns, such as would produce defects in the twisted product. The above and other advantageous features of the invention will hereinafter more fully appear from the following description, considered in connection with the accompanying drawings, in which:

Fig. 1 is a view in side elevation of a portion of a creel provided with a yarn delivery arrangement embodying the invention.

Fig. 2 is a view in front elevation of the parts of Fig. 1, as viewed from the left.

Fig. 3 is a fragmentary view illustrating individual adjustment of the yarn guides for the spindles.

Fig. 4 is a horizontal sectional view along the line 4—4 of Fig. 2, looking in the direction of the arrows.

Fig. 5 is a fragmentary view, in perspective, of a yarn guide arm and its holder.

Referring to the drawings, the creel consists of a base 1 providing a number of upright frames 2, each carrying spindles 3 in spaced vertical alinement. The spindles 3 carry yarn packages 4 of usual form, and the present invention contemplates an improved delivery arrangement for conducting individual yarn ends 5 to the top or feed rolls 6 of a twisting machine T, of any desired type, for twisting two or more yarns together as they are drawn from the packages 4.

As best shown in Figs. 1 and 2, a series of brackets 7, extending upwardly from the base 1, provide lugs 8 for receiving and supporting vertical rods 9 spaced at intervals adjacent to each row of yarn packages 4, as supported by a frame member 2. Each rod 9 carries a series of spaced collars 10, corresponding to the number of yarn packages 4 in a vertical row, with each collar 10 serving to support an arm 11 carrying

5 at its end a yarn guide 12 in the form of a "pigtail," having its opening or eye substantially coinciding with the axis of a spindle 3. Each arm 11 is bent to provide an end portion 13 extending substantially parallel to the axis of the associated spindle 3, with the guide 12 extending laterally from the portion 13. Each arm 11 is turnable on its supporting rod 9, and the collar 10 on which the arm rests, provides means 10 for supporting the arm 11 in different angular positions.

To this end, each collar 10 provides a notch 14 for receiving a projection 15 provided on the under side of the associated arm 11, and normally, the weight of the arm 11 is sufficient to maintain the projection 15 in engagement with the notch 14. Each collar 10 provides a set screw 16 for engaging the rod 9, and by setting the collars 10 for a vertical series of arms 11, with their notches 14 in slightly different angular relation on the rod 9, the associated yarn guides 12 can be offset horizontally with respect to adjacent spindles 3, as shown in Fig. 3, for a purpose which will shortly appear.

25 Referring again to Fig. 1, a rail 17 is horizontally supported by brackets 18 beneath the brackets 7, and supports a series of yarn tensions 19, of the type providing lightly engaging surfaces 20, between which yarn may be drawn, to exert a retarding effect thereon. As best 20 shown in Fig. 4, the tensions 19 are arranged in pairs in symmetrical relation with respect to a series of guides 21 mounted on a rail 22 supported by the brackets 18 in front of the rail 17. A single guide 21 is thus provided for each pair 30 of tensions 19, while a rail 23, behind the rail 17, carries a series of guides 24 corresponding in number and spacing, to the tensions 19.

35 Referring now to a vertical row of yarn packages 4, such as is shown in Fig. 2, the yarn 5 from each package is led endwise to the guide 12 of the associated arm 11, and then downwardly. Due to the differences in the angular settings of the collars 10 on the rod 9, the guides 12 are spaced horizontally as viewed in Fig. 2, and so the yarns passing therethrough are appreciably spaced apart. This spacing between yarns 5 is maintained positively as they pass to the guides 24 by a multiple guide 12a on the lowermost arm 11, which as shown in Fig. 2, provides a series of spaced eyes. The yarns then pass forwardly through a pair of tensions 19, and come together at the single guide 21, through which they pass to the feed rolls 6 of the twister. Therefore, 50 when a given pair of yarns are drawn from the

creel by operation of the twister, each yarn is withdrawn endwise from its package 4, and is conducted through the guides 12 and 12a and through the tensions 19, without any possibility of its rubbing or chafing with the other yarn of the pair that is to be twisted.

It is evident from a consideration of Figs. 2 and 3, that the guide arms 11 for the upper pair of yarn packages, are initially adjusted by means of their associated collars 10, so as to horizontally offset the guides 12 not only with respect to each other, but also with respect to the guides 12 and 12a of the pair of yarn packages immediately below. As a result of such adjustment of the guide arms 11, the yarns 5 leading downwardly from all of the packages of any vertical series, engage the lowermost multiple guide 12a at different points, definitely spaced from each other by the separated eyes, from which the yarns pass downwardly to the individual guides 24 leading to the associated tensions 19. Consequently, there is no interference between the yarns prior to their being led together in pairs, substantially at the point of twisting.

As best shown in Fig. 2, the spindles 3, as supported on alternate frame members 2, are staggered with respect to each other, as indicated by the dotted line showings of packages 4, on opposite sides of the vertical series of packages, shown in full lines. By reason of this staggered arrangement of the spindles, it is possible to readily doff any spindle 3, by swinging its associated guide arm 11 into the dotted line position. This leaves the spindle being doffed absolutely clear, thereby making it possible to place a fresh yarn package in position thereon, without in any way interfering with the withdrawal of yarn from the packages as supported in adjacent vertical series of spindles. When a guide arm 11 is swung back for doffing, the projection 15 thereon readily lifts itself out of the notch 14 on the associated collar 10, and when the arm has been turned through 180°, the projection again seats itself, to frictionally maintain the arm 11 in the doffing position.

From the foregoing, it is apparent that by the present invention, there is provided an improved delivery arrangement for creels, particularly adapted for use in connection with twisters, whereby yarn ends that are to be twisted together, are drawn from the yarn packages and conducted individually to substantially the point of twisting, without rubbing or chafing.

We claim:

1. A yarn delivery arrangement for creels, comprising means for supporting a plurality of yarn packages one above the other, means for drawing individual yarns from said packages to a point of twist, and a plurality of yarn guides angularly adjustable with respect to an axis at right angles

to the parallel axes of said packages for causing endwise withdrawal of separate yarns from said packages, and their passage to said point of twist in spaced relation.

5 2. A yarn delivery arrangement for creels, comprising a plurality of spindles for supporting yarn packages one above the other in a vertical row, a multiple eye guide bar extending horizontally below a row of spindles, and a series of yarn guides 10 individually adjustable with respect to the axes of said spindles, for causing the endwise withdrawal of separate yarns from said packages and conducting said yarns to spaced eyes on said guide bar, while entirely separated from each other.

15 3. A yarn delivery arrangement for creels, comprising a plurality of spindles for supporting yarn packages one above the other in a vertical row, a multiple eye guide bar extending horizontally below a row of spindles, and a plurality of yarn guides 20 individually adjustable about a vertical axis with respect to said spindles, for causing endwise withdrawal of separate yarns from said packages, and for conducting said yarns to spaced eyes on said guide bar, while entirely separated from each other.

25 4. A yarn delivery arrangement for creels, comprising a plurality of spindles for supporting yarn packages one above the other in spaced vertical rows, with the spindles of one row offset with respect to spindles in adjacent rows and a series 30 of pivoted yarn guides for each row of spindles, with each guide movable into the space between spindles of an adjacent row, for doffing of a spindle.

35 5. A yarn delivery arrangement for creels, comprising a plurality of spindles for supporting yarn packages one above the other in spaced vertical rows, with the spindles of one row vertically offset with respect to the spindles in adjacent rows, 40 and a series of pivotally mounted yarn guides for each row of spindles, with each guide angularly adjustable with respect to the axis of its associated spindle, and movable into the space between spindles of an adjacent row for doffing of a spindle.

45 6. A yarn delivery arrangement for creels, comprising means for supporting a plurality of yarn packages one above the other, means for drawing individual yarns from said packages to a point 50 of twist, and a plurality of arms each angularly adjustable with respect to an axis at right angles to the parallel axes of said packages, with each arm carrying a yarn guide at its free end for causing endwise withdrawal of yarn from the associated package and its passage to said point of twist while entirely separated from yarn from the other packages.
